UNITED STATES PATENT OFFICE.

GEORGE W. MALLERY, OF MYSTIC BRIDGE, CONNECTICUT.

IMPROVEMENT IN BOAT-DETACHING APPARATUS.

Specification forming part of Letters Patent No. 131,361, dated September 17, 1872.

To all whom it may concern:

Be it known that I, GEORGE W. MALLERY, of Mystic Bridge, in the county of New London and State of Connecticut, have invented certain Improvements in Boat-Lowering Apparatus, of which the following is a specification:

The invention relates to the construction of the davits and their relations to the other parts, whereby the bases or points of support change outward and inward, with a motion analogous to rolling, as the boat is moved outward and inward; also, in connection therewith, to certain braces and modes of connecting the same to the davits; also, to certain means of securing the parts in fixed positions, and to the caging or confining of the bases of the davits.

The accompanying drawing forms a part of this specification, and represents what I consider one of the best means of carrying out the invention.

Figure 1 is a cross-section of a portion of a vessel with a boat mounted. The dotted lines show the boat inboard and resting on chocks. The strong lines show it ready to be lowered. Fig. 2 is a plan view in the latter position.

Similar letters of reference indicate like parts in both the figures.

A is the deck of a ship, and D is one of the davits. There are two of these davits, one to support each end of the boat. E is the tackle by which the boat is hoisted to and lowered from the davit when the latter is in its most inclined or outboard position. The foot of the davit is bent as represented, and adapted to roll or to change its bearing in a manner analogous to the motion of a rocking-chair. M is a trough-like foot piece, having a smooth inner surface, in which the foot of the davit may roll backward and forward as the davit is drawn inboard, and allowed to incline outboard. There are transverse pins d^1 d^2 d^3 fixed in the davit, as represented, and recesses are provided in the raised sides of the casting M which receive these pins. The recesses which receive the pins d^1 d^3 are open notches; the recesses which receive the pin d^2 are covered recesses or properly-formed holes, one in each raised side of the foot piece M. As the davit is rocked to and fro on the foot piece the pins d^1 d^2 d^3 rise and sink in their respective recesses; but the

pin d^2 is never allowed to entirely escape. It is always locked or confined in the holes represented in the foot piece. The davit is guided fore and aft by divergent braces N^1 N^2 attached to a substantial slide, N, which is adapted to allow the davit to slide up and down through it. The feet of the braces N^1 N^2 are hinged to eye-bolts or knuckle-joints near the deck, as indicated by O^1 O^2 . The braces N^1 N^2 , with the slide N, may turn forward and backward, turning on the knuckle-joints O^1 O^2 to accommodate the motion as the davit is moved outboard and inboard, sliding up and down through the ring or slide N. There are two chocks, F F', to each davit. The inboard chock F is fixed; the outboard chock F' is hinged, to allow it to be folded down out of the way when the boat is to be moved into or out of its position on the chocks. The tackle I may be used to haul the davit with the attached boat forcibly inboard and to lower it again into the inclined position outboard. P is a stout pin or stop fixed in the davit, and which bears against the under face of the slide N when the davit is in its extreme outboard position. It arrests the davit and holds it firmly with the weight of the boat depending thereon. When the boat is lowered and disconnected a removable pin or key, p, is inserted to prevent the davit from moving voluntarily inboard, as it might sometimes be inclined to do when the weight of the boat is off and the ship is rolling heavily. When the davit is in its extreme inboard position the upper face of the slide N rests against a fixed pin or stop, Q, which prevents the davit from moving inboard any further. A removable key, q, may be inserted under the slide when in this position to hold the davit firmly inboard. The tackle I may be detached after the boat is properly stowed upon the chocks. In this condition the apparatus occupies very little room beyond that of the boat itself.

I propose to employ substantially the same construction of apparatus, a little differently proportioned, to serve in case there is a rail over which the boat must be lifted. In such case the chocks F F' may be higher, so as to hold the boat always at a sufficient height to be ready to move outward over from the rail; and to facilitate this operation the chocks may be mounted on transverse rails or sup-

ports, which may be slotted so as to perform the double functions of supports and of guides for the davits. In such case there may be pins or analogous locking means to hold the davit in its inboard and outboard position.

It will be understood that any ordinary or suitable construction of boat and detaching means may be employed, and also that other than the tackle I may be used to move the davit with the boat attached. The boat-fall may belay to a cleat on the side of the davit, as shown, or may be otherwise secured, as preferred. The slide N may be made in the form of a simple ring and attached to the braces N¹ N² by welding, or it may be made in other forms and attached either rigidly or by some suitable turning joints or trunnions. It is important to have a large amount of strength in these parts. The pins d¹ d³ may be permanently fixed in the davit D, but the pin d² should be removable to allow the davit to be unshipped when required.

I claim as my invention, and desire to secure by Letters Patent—

1. The davit D, formed and mounted as

shown, so as to change its base or bearing at the foot by a motion analogous to rocking, for the purposes herein specified.

2. The slide N and braces N¹ N², hinged at the points O¹ O², in combination with the davit D, formed as shown, and adapted to be inclined outboard and inboard, with a changing base or rolling support, as herein specified.

3. The stops P Q on the davit D, in combination with the keys p p, the slide N, and the stout supporting and guiding means N¹ N², to arrest the motion of the davit at the proper limits and hold them firmly, as specified.

4. The rocking-davit D, mounted in a trough-like foot piece, M, and confined by one or more transverse pins matching in holes in the sides of the foot piece, as herein specified.

In testimony whereof I have hereunto set my hand this 20th day of July, 1872, in the presence of two subscribing witnesses.

GEO. W. MALLERY.
